UNITED STATES PATENT OFFICE.

EUGENE R. SWAN, OF CEDAR RAPIDS, IOWA, ASSIGNOR TO ELLA F. SWAN,
OF SAME PLACE.

FURNACE.

SPECIFICATION forming part of Letters Patent No. 651,278, dated June 5, 1900.

Application filed March 27, 1899. Serial No. 710,631. (No model.)

To all whom it may concern:

Be it known that I, EUGENE R. SWAN, a citizen of the United States, residing at Cedar Rapids, in the county of Linn and State of 5 Iowa, have invented certain new and useful Improvements in Furnaces, of which the following is a full, clear, and exact description, reference being had to the accompanying drawings, forming part of this specification.

10 My invention relates more particularly to that class of furnaces used for heating buildings, though it is capable of other uses; and it has for its object both the burning of the fuel from beneath with a downdraft and the 15 provision of an annular chamber surrounding the fire-pot just above the grate and opening into the fire-pot to receive the gases from the coal, which are burned therein and the heat and products of combustion from which 20 pass up through suitable openings into one or more radiators and thence pass to the smoke-stack, the entire construction being designed to produce the greatest amount of heat without the production of smoke and with the 25 greatest economy of fuel.

The novelty of my invention will be hereinafter set forth, and specifically pointed out in the claims.

In the accompanying drawings, Figure 1 is 30 a central section, in side elevation, of a furnace embodying my invention. Fig. 2 is a diminished plan view of the lower radiator partially surrounding the fire-pot.

The same letters of reference are used to 35 indicate identical parts in both the figures.

A represents the tubular shell or jacket of the furnace, from the closed top of which, at the openings a, the hot-air pipes extend to registers in the different rooms in the usual or 40 any suitable manner. Within the shell A, at its bottom, is the ash-pit B, of which b represents the rear end wall and C the door in the shell for giving access to the ash-pit. D is a circular shaking-grate, of the usual or any 45 suitable construction, properly supported just over the ash-pit and directly under the fire-pot E. The fire-pot E is tubular in its main portion, with an upper dome and an annular enlarged chamber F at its lower end, just 50 above the grate, which chamber I have named the "gas-ring." There is a chute G leading from an opening in the shell A, covered by a

draft-door H and opening into the fire-pot for the introduction of fuel.

Partially surrounding the fire-pot is a tubular radiator I, in U form, as seen in Fig. 2, with closed ends and with pipes J opening from the top of the gas-ring into it. In this instance there are three of these pipes, though any suitable number may be employed. 6c

Surrounding the dome of the fire-pot and extending above the same within the shell A is the main radiator K, into the bottom of which a pipe L from the radiator I opens. The radiator K is preferably divided into two 65 compartments c d by division-plate e, which plate has an opening, as at f, to permit the products of combustion to pass up from the compartment c into the compartment d. The smoke-stack M passes out from the compartment d through the shell A and is carried to any point desired. 70

N is a door in the front of the shell giving access to the top surface of the grate for the removal of ashes, and O is a pipe opening from 75 the upper part of the fire-pot into pipe L, and a damper P is provided to cover this pipe when swung up or to cover the opening from the radiator I into the pipe L when swung downward, and this damper is controlled by 80 an operating-handle p.

When the fire is first started, the door H and its draft are closed, the draft in the door C is opened, and the damper P is let down to the position represented by the dotted lines to 85 cover the opening from the radiator I into the pipe L, and a direct upper draft is thus obtained through the grate, the fuel in the fire-pot, the pipe-hole, and radiator K to the smoke-stack in order to get the fire started. 90

As soon as the fire is started and the proper amount of fuel placed in the fire-pot the damper P is raised to close the pipe O, as shown by the solid lines, the draft in the door C is closed, and the draft in the door H is 95 opened, whereupon the draft will pass downward through the fuel and will force the gases into the annular chamber F, where they are consumed, and the products of combustion will pass up through the pipes J, first into the radiator I, thence up through the pipe L into the radiator K, heating both of these radiators very thoroughly, and then will escape through the pipe M to the chimney. 100

Owing to the location of the annular chamber F outside of the vertical area of the fire-pot the coal placed in the fire-pot does not fill or even get into the said annular chamber, 5 and the same forms a combustion-chamber for the gases expelled from the coal at the bottom of the fire-pot under the influence of the downward draft, and the burning of the fuel takes place entirely from beneath, producing 10 an intense heat with such perfect combustion that no smoke is produced. The coal in the fire-pot is replenished from time to time through the door H, as required.

While I prefer the use of the radiator I, a 15 large part of the advantage of my invention would be secured if said radiator were dispensed with and the pipes J were carried directly into the lower part of the radiator K, as will be readily understood. Again, while 20 I prefer to use the gas-ring or annular chamber F a large part of the advantage of my invention may be obtained by dispensing with said chamber and having the passages or pipes J enter the fire-pot at or near its lower 25 end above the grate. I have found from experience that these pipes will receive the distilled gases, which are consumed in them, and the operation in all other respects would be the same.

30 Having thus fully described my invention, I claim—

1. In a furnace, the combination of a fire-pot, a grate beneath the same, a radiator above the same, passages connected with the 35 lower end and upper portion of the fire-pot, respectively, and leading to the radiator, means for closing said passages, a draft-opening into the fire-pot above the fuel, and a second draft-opening below the grate, sub- 40 stantially as specified.

2. In a furnace, the combination of a fire-pot having at its lower end a projecting gas-

45 consuming chamber, a grate beneath the fire-pot, a radiator above the fire-pot, a passage connected with the gas-consuming chamber and leading to the radiator, a passage connected with the upper portion of the fire-pot; means for controlling the said passages, a 50 draft-opening into the fire-pot above the fuel, and a second draft-opening below the grate; substantially as specified.

3. In a furnace of the character described, the combination of the fire-pot E, U-shaped radiator I partially surrounding the same, the projecting gas-consuming chamber F at the 55 bottom of the fire-pot, the pipes J connecting the chamber F and radiator I, the pipe L connecting the radiator I with a superimposed radiator K, a pipe O connecting the upper end of the fire-pot with the pipe L, a damper P for 60 said pipe O and the opening from the radiator I, a draft-opening into the fire-pot above the fuel and a second draft-opening below the grate, whereby, said furnace may be burned either with a direct upward draft or with a 65 downward draft through the fuel, substantially as described.

4. In a furnace, the combination of a fire-pot, a grate beneath the same, a radiator above the same adapted for connection with a smoke-pipe, a passage connected with the 70 lower end of the fire-pot immediately above the grate and communicating with said radiator, a second passage intermediate of the upper portion of the fire-pot and the first-named passage, a damper for such passages, 75 a draft-opening into the fire-pot above the fuel, and a second draft-opening below the grate, substantially as specified.

EUGENE R. SWAN.
